UNITED STATES PATENT OFFICE.

EDWARD POSSON, OF CHICAGO, ILLINOIS.

SIDE BEARING FOR RAILWAY CARS.

1,411,222.

Specification of Letters Patent. Patented Mar. 28, 1922.

Application filed January 2, 1920. Serial No. 349,127.

To all whom it may concern:

Be it known that I, EDWARD POSSON, a citizen of the United States, residing at Chicago, in the county of Cook and State of Illinois, have invented certain new and useful Improvements in Side Bearings for Railway Cars, of which the following is a specification.

This invention relates to a side bearing for railway cars and its purpose is to provide an improved device adapted to be mounted on a railway truck to coact with a part carried by the body of the car upon relative movement of the truck about the pivot of the truck bolster.

The principal object of the invention is to provide an improved side bearing comprising a roller which automatically returns to its central position when released by the co-acting part of the car. A further object is to provide the roller of a side bearing with counter weights adapted to return it to its normal position. A further object is to provide a geared connection between the roller and its casing in order to prevent slipping of the roller and to effect an exact positioning of the roller when it returns to its initial position. Other objects relate to various other features of construction and arrangement which will appear more clearly hereinafter.

The nature of the invention will be understood from the following specification taken with the accompanying drawings in which one embodiment is illustrated.

In the drawings—

Figure 1 shows a side elevation of the improved side bearing;

Fig. 2 shows a top plan view thereof;

Fig. 3 shows a transverse sectional view on the line 3—3 of Fig. 1;

Fig. 4 shows an end elevation of one of the counter weights and its connected gear; and

Fig. 5 shows a side elevation of the device illustrated in Fig. 4.

The invention comprises a casing 10 which has a base plate 11 formed integrally with upwardly extending parallel side walls 12. The upper corners of the side walls are extended longitudinally, as shown at 13, and these extensions are united by integrally formed transverse end walls or webs 14. The side walls 12 and the end walls 14 form a substantially rectangular inclosure adapted to contain the cylindrical roller 15. The

roller 15 is adapted to travel upon a wear plate 16 which is of the same length as the base plate 11 and adapted to fit between the side walls 12. The base plate 11 and the wear plate 16 are provided at each end of the casing with registering apertures 17 adapted to be engaged by bolts or rivets in order to secure the casing in position on the car truck and to secure the wear plate in position within the casing. The roller 15 extends upwardly above the upper edges of the side walls 12, as shown in Fig. 1 where the roller is in its central position. The side walls are bounded along their upper edges by transverse flanges 19 which slope downwardly from the center of the casing toward each of the end walls 14, thus insuring a contact of the roller with a part of the car structure before said part engages any portion of the case 10.

The cylindrical roller 15 is provided with an axial bore or aperture 20 which is somewhat loosely engaged by a pin or shaft 21. This pin extends through longitudinal slots 22 which are formed in side walls 12 and it also engages apertures 23 which are formed in the hub portions 24 of the counter weights 25. The pin 21 is provided at one end with an enlarged head 21^a and at the other end it is reduced in diameter, as shown at 21^b, and riveted over a washer 26 so that the removal of the pin is prevented. Each counter weight 25 has an oblong or elliptical longitudinal cross-section and this weight is suspended below the hub portion 24 by means of an intermediate neck or stem 27.

The inner sides of the counter weights 25 are provided with segmental gears or pinions 30 which are formed integrally with the hub 24 and the depending stem portions 27, the teeth being formed on the inner side of an integral substantially semicircular web 31. The body portion 25 of the counter weight is offset outwardly from the side wall 12, as shown in Fig. 3, and the gear teeth extend downwardly into this intervening space which is occupied on each side of the casing by longitudinal rack bars 33. These rack bars are formed integrally with the side walls 12 and extend parallel with the longitudinal slots 22 so that upon movement of the pin 21 with the roller 15, the engagement of the gear 30 with the rack bars serves to elevate the depending counter weights 25 about the axis of rotation of the

roller. Upon relative movement of the car truck with respect to the body of the car, a part carried by the body bolster, for example, engages the upper peripheral part of the roller 15 and causes this roller to travel longitudinally within the casing 10 on the wear plate 16. During the travel of the roller, the counter weights 25 are elevated and as soon as the roller is released these weights tend to return to their normal depending positions. In so doing the gears 30 travel on the rack bars and automatically return the roller 15 to its central position through their engagement with the pivot pin 21. The pin 21 is mounted to rotate freely with respect to the hubs 24 of the counter weights and it is somewhat smaller in diameter than the bore 20 of the roller and the vertical width of the slots 22, thereby insuring a direct bearing of the roller 15 on the wear plate 16 and releasing the weight and strain of the roller and its load from the pin. By removing the bolts or rivets by which the wear plate and casing are secured in position, the wear plate may be readily replaced after it has become worn.

Although I have shown and described a single embodiment of the invention for purposes of illustration, it will be understood that it may be constructed in various other forms without departing from the scope of the appended claims.

I claim:

1. A railway side bearing comprising a casing, a roller mounted within said casing, a rack bar, a gear mounted independently of said roller and adapted to coact with said rack bar during the movement of said roller, and a weight adapted to return said roller to normal position.

2. A railway side bearing comprising a casing, a roller mounted therein, a pin engaging said roller, a weight carried by said pin, a rack bar, and a segmental gear adapted to coact with said rack bar to elevate said weight upon the movement of said roller.

3. A railway side bearing comprising a casing, a roller mounted in said casing, an axial pin engaging said roller, a gear connected to said pin, means engaging said gear for controlling the travel of said roller and a weight for returning said roller to normal position in said casing.

4. A railway side bearing comprising a casing, a roller mounted in said casing, an axial pin engaging said roller, a weight suspended from said pin, a gear movable with said weight, and a rack bar meshing with said gear.

5. A railway side bearing comprising a casing, a roller mounted in said casing, an axial pin engaging said roller, a weight sus-

pended from said pin, a gear movable with said weight, and a rack bar formed integrally with said casing and meshing with said gear.

6. A railway side bearing comprising a casing having a longitudinal slot, a roller mounted in said casing to travel parallel to said slot, a pin engaging said roller and said slot, a gear mounted on said pin, and a rack bar extending parallel to said slot and meshing with said gear.

7. A railway side bearing comprising a casing having a longitudinal slot, a roller mounted in said casing to travel parallel to said slot, a pin engaging said roller and said slot, a gear mounted on said pin, a rack bar extending parallel to said slot and meshing with said gear, and a counter weight suspended from said pin and movable with said gear.

8. A railway side bearing comprising a casing having a longitudinal slot therein, a roller mounted in said casing, said roller having an axial bore, a pin loosely engaging said bore and extending through said slot, a counter weight freely suspended from said pin, and means coacting with said weight to effect the elevation thereof above said pin upon travel of said roller.

9. A railway side bearing comprising a casing having a longitudinal slot therein, a roller mounted in said casing, said roller having an axial bore, a pin loosely engaging said bore and extending through said slot, a counter weight freely suspended from said pin, a gear movable with said weight, and a rack bar attached to said casing and meshed with said gear.

10. A railway side bearing comprising a casing having a longitudinal slot therein, a roller mounted in said casing, said roller having an axial bore, a pin loosely engaging said bore and extending through said slot, a counter weight freely suspended from said pin, a gear formed integrally with said counter weight and having its axis coincident with the axis of said pin, and a rack bar formed integrally with said casing and meshing with said gear.

11. A railway side bearing comprising a casing having parallel side walls, said side walls having longitudinal slots therein, a roller mounted in said casing between said side walls, an axial pin engaging said roller and passing through said slots, weights suspended from the ends of said pin, gears movable with said weights about the axis of said roller, and rack bars mounted on said side walls and meshing with said gears.

In testimony whereof, I have subscribed my name.

EDWARD POSSON.
